ALBERT W. HAPPEL, OF TOLEDO, OHIO, ASSIGNOR TO KENT-OWENS MACHINE COMPANY,
OF TOLEDO, OHIO, A CORPORATION OF OHIO

METAL-WORKING MACHINE

Application filed March 31, 1928. Serial No. 266,148.

This invention relates to metal working machines, and especially to mechanism for punching holes in metal or for performing other similar operations.

The general object of the invention is to provide mechanism whereby a punch or similar tool may be operated with an adjustable stroke, thus making it possible to set the same so that it will always come to rest at a point just above the material. With the present construction, however, the tool does not come to rest until it has been withdrawn far enough to strip the work therefrom and has been again advanced to the desired position. In case the adjustment is such that the tool comes to rest in a higher position, the tool may be brought down closer to the surface of the material by means of a hand operated lever. The tool has what may be termed a full floating support, so that it will normally remain in any position to which it is adjusted. This insures the utmost convenience in operating the machine, either when punching holes in materials of various thickness or when punching a large number of holes in material of uniform thickness.

The specific construction of the invention in the form which at present seems most desirable, together with its mode of operation, will be more particularly described in connection with the accompanying drawings, in which—

Figure 1 is a vertical longitudinal section through the front end of a punching machine embodying the invention, the parts being shown in position for operation.

Fig. 2 is a view similar to Fig. 1, but with the parts in position for idling.

Fig. 3 is a similar view wherein the punching stroke is adjusted to the work.

Fig. 4 is a front elevation of the portion of the machine shown in Fig. 1.

As shown in the drawings, the mechanism constituting the subject matter of the invention is mounted in a frame 5 which has a forwardly extending seat 6 for supporting a die 7. Above the seat 6 the frame is provided with a head 8, to which is secured a front housing plate 9 to form a vertical guideway 10 for a plunger 11 to which the punch 12 is

secured. The usual stripper 13 is also secured to the head and is formed with a hole 14 through which the punch 12 operates.

The plunger 11 is formed at its sides with arms 15 which extend upwardly in the side portions of the guideway 10. A ram 16 is supported by links 17 from a rocker arm 18 which is mounted on a shaft 19 and is adapted to be continuously rocked in a well known manner. The ram 16 is adapted to move up and down between the arms 15 and is formed with a lug which is guided in a channel 20 formed in one of the arms.

The plunger 11 is connected at its rear side by a link 21 to an arm 22 which is secured to a shaft 23 mounted for rocking movement in the frame. A rearwardly projecting arm 24 is secured to the shaft 23 and has an extension 25 which is connected by a spring 26 to a fixed part of the frame. The spring 26 is under sufficient tension to counterbalance the weight of the plunger 11 and the punch carried thereby. The extension 25 has a threaded connection with the arm 24 so that it may be adjusted longitudinally until the proper counterbalance is attained. By this means a full floating support is secured for the punch 12 and the latter will remain in any position to which it is adjusted, until it is acted upon by some positive force. A hand lever 27 is secured to the rock shaft 23, whereby the punch may be adjusted to any desired position.

As the rocker arm 18 moves back and forth to reciprocate the ram 16 power may be transmitted from the ram to the plunger 11 and punch 12 through the medium of a block 28, when the latter is in the position shown in Fig. 1. This block is mounted to slide horizontally forwardly or rearwardly on a rearward extension 29 of the plunger 11. For controlling the position of the block 28 the latter is connected by a link 30 to an arm 31 which is secured to a rock shaft 32 mounted in the frame 5. An arm 33 secured to the shaft 32 is connected by a spring 34 to a fixed part of the frame and the tension of the spring 34 is sufficient to hold the block 28 retracted, as shown in Fig. 2, or to return it to that position after it has been advanced.

When it is desired to operate the punch, therefore, the shaft 32 is rocked to advance the block 28 into the path of the ram, whereupon the punch will be actuated upon the next downward stroke of the ram. As soon as the block 28 is released and withdrawn from beneath the ram, the latter will reciprocate idly without actuating the punch.

The plunger 11 is formed with two ears 35 extending forwardly from the upper portion of the arms 15, and between these ears a pawl 36 is pivotally supported. The pawl 36 is weighted on the front side as shown at 37 so that it normally swings by gravity 40 into contact with the ram 16. The ram is formed on its front side with a lug 38 having an inclined face, and below this lug and spaced therefrom is a shoulder 39. The pawl 36 is formed with a rearward projection 40 adapted to cooperate with the lug 38 upon the downward stroke of the ram or with the shoulder 39 upon the upward stroke of the ram. The lower end of the pawl 36 is formed with a notch 41 adapted, under certain conditions, to be engaged by the end of a latch 42, which is mounted within a channel 43 in the plunger 11 and urged upwardly by a small spring 44.

In the operation of the punch, as the block 28 is moved into the position shown in Fig. 1, the ram 16, upon its downward stroke, strikes the block 28 and thereby moves the plunger 11 and punch 12 downwardly. Upon the return stroke of the ram 16 the shoulder 39, which engages the projection 40 on the pawl 36, raises the punch in readiness for the next stroke. Thus the punch moves up and down with the ram 16 as long as the block 28 remains in its operative position. When the block 28 has been retracted, as shown in Fig. 2, the next downward stroke of the ram 16 will cause the lug 38 to engage the upper face of the projection 40 and will throw the pawl 36 forwardly. The latch 42 under the influence of the spring 44 will then engage the notch 41, latching the pawl in the position shown in Fig. 2 so that the ram 16 may operate idly until the block 28 is again advanced. The block upon its advance depresses the latch 42 and releases the pawl 36, so that the ram is again locked to the plunger, as shown in Fig. 1.

With the construction thus far described, when the block 28 is retracted to inoperative position the punch will normally come to rest in its uppermost position and will remain in that position by reason of its full floating support. When the material is brought into position to be punched the punch may be lowered into proximity to the material by means of the hand lever 27.

When punching a large number of holes in material of uniform thickness, however, it is desirable to adjust the stroke of the punch so 65 that it will automatically come to rest in the

desired position. For this purpose one of the links 17 may be formed with a threaded collar 45 in which is mounted an adjustable pin 46. This pin may be adjusted so that after the pawl 36 has been thrown outwardly and is held by the latch 42 the next downward stroke of the ram 16 will cause the end of the pin 46 to engage the plunger 11 and lower it to the proper position, as shown in Fig. 3.

It is also to be particularly noted that the plunger 11, after each working stroke, is withdrawn to the fullest extent of its upward movement, so that the work is completely stripped from the punch, and that the plunger is subsequently advanced, either by operation of the hand lever 27 or of the pin 46, to the position shown in Figure 3 where the work may be accurately gaged, before the block 28 is shifted forwardly for the next operation of the punch.

From the foregoing description it will be noted that the full floating support for the punch makes it possible to adjust the same to the work with the utmost facility, while the adjustable pin 46 makes it possible to effect the adjustment of the stroke so that the punch will always come to rest in the most favorable position for gauging the work to be performed. While I have shown and described in detail the construction which at present seems most desirable for this purpose, it is apparent that the same may be considerably modified without any material departure from the scope of the invention as herein claimed.

What I claim is:

1. In a machine of the class described, a reciprocable plunger, means for securing a tool thereto, a ram reciprocable in the same direction as the plunger, a block movable into operative position between the ram and the plunger for transmitting power from the one to the other, means rendered operative by the movement of the block to operative position, to cause the return movement of the ram to be positively transmitted to the plunger, and means for disconnecting the ram from the plunger upon withdrawal of the block, but only after the ram has completed its upward stroke and started to return.

2. In a machine of the class described, a reciprocable plunger, means for securing a tool thereto, a ram reciprocable in the same direction as the plunger, control means effective, when moved to operative position, to connect the plunger to the ram so as to be reciprocated thereby, and means for disconnecting the ram from the plunger after the control means is moved to inoperative position, said disconnecting means being effective only after the ram has completed its upward stroke and started to return.

3. In a machine of the class described, a reciprocable ram, a plunger reciprocable in the same direction as the ram, means for op-

tionally connecting the plunger to the ram to be operated thereby, and adjustable means connected with the ram for advancing the plunger to a predetermined position after the 5 plunger is disconnected from the ram.

4. In a machine of the class described, a reciprocable ram, a plunger located in advance of the ram, a block, means for inserting the block between the ram and the plunger to cause the plunger to advance with the ram, a pawl operable to lock the plunger to the ram, and means to move the pawl to inoperative position during the downward stroke of the ram after the block is withdrawn.

5. In a machine of the class described, a reciprocable ram, a plunger located in advance of the ram and reciprocable in the same direction, a block, means for inserting the block between the ram and the plunger to cause the plunger to advance with the ram, a pawl mounted on one of the reciprocating members and engageable with the other reciprocating member to cause both members to 25 return simultaneously, means to move the pawl into inoperative position during the downward stroke of the ram after the block is withdrawn, and means to latch the pawl in its inoperative position.

6. In a machine of the class described, a reciprocable ram, a plunger located in advance of the ram and reciprocable in the same direction, a block insertible between the ram and the plunger to cause the plunger to advance with the ram, a pawl mounted on one of the reciprocating members and engageable with the other reciprocating member to cause both members to return simultaneously, means to move the pawl into inoperative position after the block is withdrawn, and a 40 spring latch to hold the pawl in its inoperative position, said latch being in the path of the block and actuated thereby, as the block is advanced to operative position, to release the pawl and permit it to return to operative position.

7. In a machine of the class described, a reciprocable ram, a plunger located in advance of the ram, a block, means for moving the block to operative position between the ram and the plunger for causing the plunger to advance with the ram, a pawl operable to return the plunger with the ram, means to move the pawl to inoperative position during the downward stroke of the ram after the block is withdrawn, and independent adjustable means for determining the position in which the plunger comes to rest after the block and pawl are moved to inoperative position.

8. In a machine of the class described, a tool carrying member guided for reciprocation, a ram, means for optionally transmitting reciprocatory movement from the ram to 65 said member, means for counterbalancing

said member to cause it to remain normally in any position to which it has been moved, and a hand lever connected with said member and operable to move it in the direction of its reciprocatory movement after it has been disconnected from the ram and while the latter continues to reciprocate.

9. In a machine of the class described, a tool carrying member guided for reciprocation, a ram, means for optionally transmitting reciprocatory movement from the ram to said member, a stripper cooperating with said member, and means for bringing said member to rest in a predetermined position only after it has been withdrawn past the stripper and again advanced, while the ram continues to reciprocate.

10. In a machine of the class described, a tool carrying member guided for reciprocation, a ram, means for transmitting reciprocatory movement from the ram to said member, a stripper cooperating with said member, means for disconnecting said member from the ram only after the tool has been withdrawn past the stripper, and other means for subsequently advancing said member to a predetermined position.

11. In a machine of the class described, a reciprocable plunger, means for securing a tool thereto, a ram reciprocable in the same direction as the plunger, means optionally operable to cause the reciprocating movement of the ram to be positively transmitted to the plunger, and means to cause the plunger to come to rest in a predetermined position only upon its return stroke, after being carried with the ram to its uppermost position and disconnected therefrom.

12. In a machine of the class described, a reciprocable plunger, means for securing a tool thereto, a ram reciprocable in the same direction as the plunger, means for optionally connecting the plunger to the ram to reciprocate therewith or disconnecting it after it has completed its upward stroke, so that the ram alone reciprocates, and means for moving the plunger downwardly a limited distance after it is disconnected, said last mentioned means being adjustable to vary the position in which the plunger finally comes to rest.

In testimony whereof, I have hereunto signed my name to this specification.

ALBERT W. HAPPEL.
